UNITED STATES PATENT OFFICE.

JOHN AZAMBER, OF PITTSBURG, KANSAS.

BIN MOUNTING FOR KITCHEN CABINETS.

Application filed July 11, 1922. Serial No. 574,232.

To all whom it may concern:

Be it known that JOHN AZAMBER, a citizen of France, residing at Pittsburg, in the county of Crawford and State of Kansas, has invented new and useful Improvements in Bin Mountings for Kitchen Cabinets, of which the following is a specification.

The object of the invention is to provide efficient means for mounting flour, meal and sugar and like bins in kitchen cabinets and like structures under conditions affording ready access for the dispensing of the contents thereof and convenient means for refilling the bin without involving the operator in the exertion of lifting or supporting the weight of the bin and its contents which, when of relatively large proportions, is of a weight rendering it inconvenient to handle; and with this general object in view 20 the invention consists in a construction and combination of parts of which a preferred embodiment is shown in the accompanying drawings, wherein:—

Figure 1 is a front view of a bin of the type indicated having a mounting embodying the invention and housed within a casing which may constitute a compartment of a kitchen cabinet or like structure.

Figure 2 is a vertical sectional view of the same showing in dotted lines the position of the parts when the bin is withdrawn from the casing and lowered to facilitate refilling.

Figure 3 is a perspective view of the mounting detached from the cabinet.

The mechanism consists essentially of bin supporting arms 10 pivotally mounted as at 11 upon base plates 12 which are securely fastened to the walls 13 of a casing in which the bin 14 carried by said arms is adapted to be housed and which in practice may constitute a compartment of a kitchen cabinet, the engagement of the bin with the arms being detachable as by consisting of headed pins 15 projecting laterally from the bin for reception by seats 16 consisting of notches formed in the extremities of said arms, together with means tending to swing the bin supporting arms into the casing so as to house the bin therein in a pendent position so that the contents may be withdrawn through a dispensing outlet 17 in the lower end of the bin. The bin is thus mounted for swinging movement between the extremities of the supporting arms so as to maintain an upright posi-

tion in all adjustments of the supporting arms, and may be swung forward at its lower end in withdrawing the contents therefrom to insure discharge of the contents into a suitable receptacle, and to facilitate such manipulation and also the drawing forward and downward of the bin when it is desired to refill the same. The bin is preferably provided near its lower and upper ends with handles 18 and 19.

In the construction illustrated the means for holding the supporting arms with the bin suspended thereon and thus carrying all or a part of the weight of the bin and its contents when the bin is loaded or fully charged, consists of a yoke 19 having side arms 20 which have sliding connection with the supporting arms 10 and are also connected adjacent their rear ends by links 21 with rearwardly directed feet or terminals 22 of said supporting arms, to the end that a rearward strain applied to the cross bar of the yoke 19 by means of the coiled return springs 23 or the equivalents thereof will be communicated through the links 21 to the terminals or feet of the supporting arms to cause a folding or upward and rearward swinging movement of the latter. Said springs are anchored at their rear ends to the attaching plates 12, and in order that there may be an opportunity for movement of the supporting arms independently of the yoke as for example when the apparatus is in position to house the bin and it is desired to move the bin forward slightly so as to more readily withdraw a portion of the contents thereof into a cooking utensil or the like, the arms of the yoke are slidingly fitted in guides 24 and traversed by rollers 24' provided on the supporting arms 10, while disengagement of the arms of the yoke from said guides is prevented by stops 25 consisting of the deflected or hook shaped extremities of the yoke arms serving to engage the forward edges of the supporting arms. Thus the yoke is drawn forward as the supporting arms are swung downwardly and outwardly.

In order that the bin may be supported in a preferred adjusted position and particularly in a depressed position as shown in dotted lines in Figure 2 to facilitate the refilling thereof, the supporting arms carry pivotal latches 26 for engagement with toothed racks 27 formed in this instance on the attaching plates 12, said latches being

provided with inwardly directed stems or finger holds 28 for manipulation by the operator when it is desired to permit the springs to return the supporting arms with the bin to the folded and housed position within the casing.

Also rubber sleeves 29 may be slidingly fitted on the supporting arms for adjustment to bear upon the surface of the cabinet, 10 table or other support when the supporting arms are extended, to avoid marring the table or support.

The yoke being held in its folded position by the actuating springs when the parts are 15 in the housed relation in the casing, it will be noted, by reference to Figure 2, that there is a margin of play providing for movement of the bin supporting arms independently of the yoke, or until they impact with the 20 stops 25. In such a position, the bin supporting arms are so nearly vertical that but a slight pressure against the front side of the bin is sufficient to push the latter rearwardly into the casing when it is desired 25 to close the casing to completely house the bin. When the arms are in the position to contact with the stops, the bin is disposed in the dispensing position but when it is 30 desired to fill the latter, the arms are drawn forwardly and impacting with the yoke, motion is communicated to the latter and it and the arms swing outwardly to dispose the bin in a position for refilling, the springs 23 in 35 this operation being under tension and serving to return the parts to their normal housed position when the pivotal latches 26 are released by means of their finger holds 28.

Having described the invention, what is 40 claimed as new and useful is:—

1. In combination with a dispensing bin, a mounting having pivotal supporting arms between the extremities of which the bin is suspended, a spring actuated yoke having

arms slidingly engaged with the supporting 45 arms and provided with stops for limiting the movement of the supporting arms independently of the yoke after they have reached a certain position with respect to the latter, the supporting arms being provided 50 with rearwardly directed terminals, and links having terminal pivotal connections with said rearwardly directed terminals and with the arms of the yoke at points between the cross bar thereof and the point of engagement of the supporting arms therewith to communicate rocking movement of the supporting arms to the yoke.

2. A mounting for bins having pivotal supporting arms between the free ends of 55 which the bin is suspended, a yoke carried by the supporting arms and having link connections with rearwardly deflected terminals of the supporting arms adjacent the pivotal points thereof, the arms of the yoke 60 having limited sliding connections with the supporting arms, and retraction springs connected with the yoke for yieldingly resisting the forward movement of the supporting arms.

3. A mounting for bins having pivotal supporting arms between the free ends of 65 which the bin is suspended, a yoke carried by the supporting arms and having link connections with rearwardly deflected terminals of the supporting arms adjacent the pivotal points thereof, the arms of the yoke 70 having limited sliding connections with the supporting arms, retraction springs connected with the yoke for yieldingly resisting the forward movement of the supporting arms, and means for locking the supporting arms against the rearward movement normally imposed by said spring.

In testimony whereof he affixes his signature.

JOHN AZAMBER.
